UNITED STATES PATENT OFFICE

164,416

KITCHEN CABINET

Michael Hallward, Swampscott, Mass.

Application June 30, 1950, Serial No. 10,871

Term of patent 14 years

(Cl. D33—13)

To all whom it may concern:

Be it known that I, Michael Hallward, a citizen of Great Britain, residing at Swampscott, county of Essex, State of Massachusetts, have invented a new, original, and ornamental Design for Kitchen Cabinet, of which the following is a specification, reference being had to the accompanying drawing, forming a part hereof.

I claim:

The ornamental design for a kitchen cabinet, as shown.

MICHAEL HALLWARD.
